(57) **CLAIM**

The ornamental design for a golf ball, as shown and described.

DESCRIPTION

The patent or application file contains at least one drawing executed in color. Copies of this patent or patent application publication with color drawings(s) will be provided by the Office upon request and payment of the necessary fee.

FIG. 1 is a top perspective view showing our new design for a golf ball with a red center line and parallel blue lines;

FIG. 2 is a top plan view of FIG. 1; and,

FIG. 3 is a side elevation view of FIG. 1.

The broken lines represent elements of the golf ball that form no part of the claimed design.
